UNITED STATES PATENT OFFICE.

CARL SCHRAYSSHUEN, OF PROVIDENCE, RHODE ISLAND, ASSIGNOR TO SPEIDEL CHAIN CO., OF PROVIDENCE, RHODE ISLAND, A FIRM COMPOSED OF FREDERICK SPEIDEL AND EUGEN SPEIDEL, BOTH OF PFORZHEIM, GERMANY.

CHAIN.

Application filed September 8, 1925. Serial No. 54,971.

To all whom it may concern:

Be it known that I, CARL SCHRAYSSHUEN, a citizen of the United States, residing at Providence, in the county of Providence and State of Rhode Island, have invented certain new and useful Improvements in Chains, of which the following is a specification.

This invention relates to an improved construction of link for ornamental chains for personal wear; and has for its object to provide simple and effective construction of such a link by interlocking together two loop links, one within the other.

15 A further object of the invention is to set two elongated loop links one within the other, the side arms of each being depressed at intervals along their length and forming corresponding inward projections along 20 their inner surfaces, the projections of one link extending into the spaces between the projections of the other link to present the appearance of a plurality of separate links connected together.

25 With these and other objects in view, the invention consists of certain novel features of construction, as will be more fully described, and particularly pointed out in the appended claims.

30 In the accompanying drawings:

Figure 1 is a view illustrating a plurality of my compound links flexibly connected by connector links.

Figure 2 is a perspective view of one of 35 the outer links of the compound link as cut from sheet stock.

Figure 3 shows this outer loop link illustrated in Figure 2 as having the outer surface of its side arms depressed at intervals 40 forming corresponding inward projections on its inner surface.

Figure 4 is a perspective view of the inner link having inward projections along its inner surface forming spaces between the projections.

Figure 5 shows a perspective view of the inner link as connected to the outer link by forcing the inward projections of the outer link into the space in the inner link.

50 Figure 6 is a central sectional view on line 6-6 of Figure 5, showing the projections of the outer link as extending through the spaces in the inner link.

Figure 7 is a sectional elevation taken at

right angles to that of Figure 6, showing the 55 spaces in the inner link through which the projections of the outer link extend.

It is found in the practical construction of fancy shaped, ornamental chain links for personal wear, of advantage to blank the 60 links into elongated loop form and to interlock two of these elongated links together by forming spaces at intervals along the inner link, by forcing portions of the side arms together and forming similar spaces 65 and projections on the outer link, the projections of the outer link extending into the spaces of the inner link to lock the two together and to present the appearance of the so-called "Boston" link; and the following 70 is a detailed description of the present embodiment of my invention and showing one construction of link by which these advantageous results may be accomplished.

With reference to the drawings, 10 designates the outer link member of the compound link, which is preferably cut from sheet stock forming a one-piece elongated loop-shaped link. The opposite arms of this link are then pressed inwardly at intervals 80 along their length as at 12, causing the stock on the inner surface to extend toward each other as at 13, but these projections are primarily left spaced sufficiently to receive the inner link member 14 between them.

This inner link member 21 is constructed 85 similarly to the outer link member in that its side arms 15 are pressed, swaged or bent inwardly as at 16 at intervals along its length forming inwardly-extending projections 17 on its inner surface thereby providing a plurality of spaces or loops between the inwardly projecting portions. The inner link thus formed is then passed into or between the prepared arms of the outer link

90 to set at right angles thereto then the arms 11 of the outer link are forced inwardly causing the inward projections 13 thereof to extend through the spaces 18 in the inner link interlocking the two links together in such position as to present the appearance 95 of the linking together of a plurality of square links to give the appearance of the so-called "Boston" link, the length of the inner link being less than that of the outer link for the reception of the connecting links 20 by which these compound links are flexibly joined together.

My improved chain link is very simple and practical in construction, is very ornamental in appearance, and is strong and durable and by its construction the much desired appearance of the "Boston" type of link is obtained by a very inexpensive method of construction.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a chain, two elongated loop links set one within the other, each having depressions in its side arms forming corresponding projections on their inner surfaces extending toward each other, the inward projections of one extending into the spaces in the other interlocking the two together to present the appearance of a plurality of separate links.

2. In a chain, an elongated loop link having its side arms bent inwardly toward each other at intervals and another similar elongated loop link set between the arms of and at a right angle to the first link with its inwardly-extending portions projecting toward each other and abutting in the spaced openings in the first link to present the appearance of a plurality of separate interlocking links.

3. A chain link formed of two elongated loop links set one within and at right angles to each other, the side arms of each being shaped to form spaced depressions along their outer surfaces and corresponding inward projections along their inner surfaces, the projections of one link extending into the spaces of the other link to present the appearance of a plurality of separate links connected together, spaces being left at the ends of the outer links for the reception of connecting links.

In testimony whereof I affix my signature.
CARL SCHRAYSSHUEN.
